SUPPORTING ATTACHMENT FOR TABLES
AND THE LIKEVincent Biska, Niles, and John F. Baas,
Chicago, Ill.

Application May 22, 1939, Serial No. 274,922

2 Claims. (Cl. 243—226)

The invention relates to supporting attachments for tables and the like, the primary object being the provision of an improved supporting attachment of the character indicated especially adapted for attachment to restaurant tables or the like for the support of ladies' purses or other articles, which is of simple construction, highly efficient in use and capable of economical production.

Other objects will appear hereinafter.

The invention consists in the combinations and arrangements of parts hereinafter described and claimed.

The invention will be best understood by reference to the accompanying drawing forming a part of this specification and in which

Fig. 1 is a side view of a supporting attachment embodying the invention and shown in position of use, attached to the edge of a table;

Fig. 2 an enlarged top plan view of the supporting attachment removed;

Fig. 3 an outer end view of the same;

Fig. 4 a view of a modified form of construction illustrated as attached to the apron of a table;

Fig. 5 an enlarged top plan view of the attachment shown in Fig. 4; and

Fig. 6 an outer end view corresponding with Fig. 5.

The embodiment of the invention illustrated in Figs. 1, 2 and 3 consists of a combined clamping and supporting member made from a single piece of spring wire, the central portion of which is bent to form one substantially rectangular clamping jaw 10 adapted and arranged to clamp flat against the under side of a table top 11 as shown in Fig. 1. The inner ends of the clamping jaw 10 are extended downwardly and forwardly to form the portions 12, then upwardly to form the portions 13 extending above the table top, then inwardly to contact with each other forming the portions 14, then inwardly in contact with each other forming the portions 15, said portions 15 being preferably electrically welded together. The inner ends of the portions 15 are then extended inwardly and divergently and then outwardly to form the loops 16 and a clamping jaw in parallel relation with said jaw 10, the outer portions of said loops being then bent downwardly past the outer edge of the table top to form the vertical bars 17 lying adjacent said vertical bars 13, said adjacent bars 13 and 17 being electrically welded together at their upper portions to increase the spring action of the clamp thus formed.

The lower ends of the vertical bars 17 are then extended rearwardly in parallel relation to form

the bars 18 and then divergently to form the bars 19, the inner ends of the bars 19 being formed into spring hinge coils 20 as shown. The lower ends of the coils 20 are extended outwardly to form the side bars 21 of a supporting frame, the outer ends of the bars 21 being extended toward each other to contact and then inwardly to form the medial bars 23 of the frame, said bars 23 being preferably electrically welded to each other. At their rear ends the bars 23 are extended divergently and inwardly to form the frame bars 24 and the outer ends 25 of said frame bars are electrically welded to the side bars 21 adjacent hinge coils 20 as best shown in Fig. 2. A metallic split sleeve 26 is preferably clamped over the inner ends of the bars 22 to firmly secure the same together and constitute a handle or finger piece.

By this arrangement a combined spring clamp and supporting member is provided made from a single piece of spring wire which is adapted and arranged to be clamped to the edge of a table top or the like as indicated in Fig. 1. As shown, the clamping jaws are arranged to co-operate with each other to clamp a table edge or the like in substantially parallel relation and so that the pressure thereof will not be concentrated at any one point but will be uniformly distributed so as to avoid marring or damage to a table top. When so mounted, the supporting frame 21—22—23—24—25 constitutes a downwardly yielding support which may be readily swung downwardly to receive a lady's purse or the like and will automatically swing upwardly under the spring action of the coiled hinges 20 to clamp and hold said purse or other article, as will be readily understood. By this arrangement a simple and convenient supporting attachment is provided which may be readily attached to restaurant tables or the like for the obvious convenience of the patrons or persons using said tables. The specific form and arrangement of parts is a simple and effective one for the purpose.

If desired, the bars of the clamping members 10 and 16 may be covered with rubber to prevent marring of the polished table tops and the split sleeve 26 also covered with rubber to facilitate handling of the same.

In the embodiment of the invention illustrated in Figs. 4, 5, and 6, a clamp is shown adapted and arranged to attach to the apron of a table. To this end the central portion of the spring wire is bent to form a rectangular clamping jaw 27 adapted to fit against and engage the inner side of the apron 28 of the table 11. The sides of the clamping jaw 27 are then extended inwardly and

downwardly to form the side bars 29 and then outwardly beyond the outer edge of the apron 28. At the outer edge of the apron, the wires are extended toward each other to form the bars 30 and then upwardly in contact with each other to form the bars 31, the bars 31 being electrically welded together. The upper ends of the bars 31 are then extended upwardly and divergently and then downwardly to form the loops and side bars 32 and 33, the lower ends of the side bars 33 being extended rearwardly to form the side bars 34 in contact with the corresponding side bars of the clamping member and being electrically welded thereto. At their rear ends the side bars 34 are extended upwardly to form the vertical bars 35 and then rearwardly in parallel relation to form the parallel bars 36 leading to the forward ends of the divergent bars 19 which in turn lead to the coiled hinges 20 as before. By this arrangement a spring clamp is provided by means of which the attachment may be readily secured to and mounted on the lower edge of the apron 28 of a table or the like. Otherwise the construction and operation is the same as that already described.

While we have illustrated and described the preferred form of construction for carrying the invention into effect, this is capable of variation and modification without departing from the spirit of the invention. We therefore do not wish to be limited to the precise details disclosed, but desire to avail ourselves of such variations and modifications as fall within the scope of the appended claims.

We claim:

1. An attachment of the class described made from a single piece of spring wire bent centrally

5 to form one jaw of a spring clamp adapted and arranged to engage over the edge of a table or the like and rest flat against the underside thereof, the sides of said clamp jaw being bent downwardly and outwardly and then upwardly to extend above the top of the table, then toward each other to contact and be secured together, then inwardly and divergently and then outwardly and downwardly to form the other spring clamping jaw in parallel relation with said first mentioned jaw, the ends of said wire being then extended inwardly and divergently, formed into coiled spring hinges, and then outwardly to the edge of the table, then toward each other into contact and inwardly and divergently to form a downwardly swinging supporting frame.

2. An attachment of the class described made from a single piece of spring wire bent centrally to form one jaw of a spring clamp adapted and arranged to engage over the lower edge of a table apron or the like, the sides of said clamp jaw being bent downwardly and inwardly and then outwardly to extend beyond the outer side of the table apron, then toward each other to contact and be secured together, then outwardly and divergently and then inwardly and upwardly to form the other spring clamping jaw, the ends of said wire being then extended inwardly and divergently, formed into coiled spring hinges, and then outwardly to the edge of the table, then toward each other into contact and inwardly and divergently to form a downwardly swinging supporting frame.
